RICHARD C. LEAKE, OF ROCHESTER, NEW YORK, ASSIGNOR TO GENERAL RAILWAY SIGNAL COMPANY, OF ROCHESTER, NEW YORK.

TRAIN CONTROL.

Application filed September 11, 1924. Serial No. 737,159.

This invention relates to automatic train control systems, and more particularly to a protected cut-out device for such systems.

It is generally conceded that any train control system, regardless of how well it is constructed, will at some time or other fail mechanically or electrically so that the brake control device thereof must be such that it may be cut out by the engineer so that he can complete the run. In the majority of train control systems heretofore proposed, the apparatus for applying the brakes consists of apparatus pneumatically operated, and the present invention relates more particularly to a pneumatic cut-out device. It is not considered safe to merely require the engineer to break a seal when he places the cut-out device in its active position; and in accordance with the present invention it is proposed to provide means for applying the brakes unless the engineer operates a suitable manually operable means at least once in a predetermined interval of time, and to provide audible means for advising the engineer when this interval of time is about to elapse.

Also, in order that the engineer may be constantly reminded that the automatic system has been cut out of service and that the responsibility for the safety of the train is wholly in his hands, it is proposed to provide an indicating means showing that the system is cut out and to locate this indicating means at a point in the cab where the engineer will frequently look during the ordinary operation of his train. As shown, this indicating means is associated with the usual pressure gauge of the air-brake system.

Other objects, advantages and characteristic features of the present invention will appear as the description progresses.

In describing the invention in detail, reference will be made to the accompanying drawings in which:—

Figure 1 shows a simple type of pneumatically operated automatic brake applying mechanism adapted to be used in practically any type of train control system, together with means embodying the present invention for cutting out this mechanism;

Fig. 2 is a sectional elevation of the time element device forming part of the cut-out apparatus shown in Fig. 1, this section being taken on a line 2—2 in Fig. 1 looking in the direction of the arrows; and

Fig. 3 illustrates in detail the changeable

exhibitor of indicator shown in Fig. 1 which is located back of the dial of the air-brake pressure gauge.

In order to show how the cut-out device of the invention may be employed in a train control system to prevent an automatic brake application by reason of failure of such system, a very simple type of application valve AV has been shown, together with a portion of the piping arrangement of the usual air brake system to which it is connected.

This application valve AV comprises a casing or cylinder 1 in which a slide valve 2 is moved back and forth by a piston 3, normally held in its extreme lefthand position by a compression spring 4, this cylinder having a cap 5 on the end thereof which limits the movement of the piston 3 in its travel upon an automatic brake application. The slide valve 2 is held against its seat by main reservoir pressure supplied through pipe 6; and this air pressure flows to the right hand side of the piston 3 through the leakage hole or port 7. Under normal conditions, main reservoir pressure exists on both sides of this piston 3 and it is moved to the position shown by the spring 4, because main reservoir pressure is confined in the portion of the cylinder to the right of piston 3 under such normal conditions by the valve 8 of an electro-pneumatic valve EPV, this valve normally being held closed against the pressure of a spring 9 by an armature 10 attracted downwardly by current flowing in a winding 11. Upon de-energization of the winding 11, the armature 10 and in turn the valve 8 move upwardly, thereby allowing pressure to escape from the right hand side of piston 3 through pipe 12 and the exhaust 13 to atmosphere. The discharge through the valve EPV is larger than the leakage port 7, and hence the pressure on the right hand side of piston 3 will drop quickly, thereby causing this piston to move to its extreme right hand position.

When the slide valve 2 assumes its operated righthand position, it blanks the port leading to a pipe 14 which normally supplies main reservoir pressure to the engineer's brake valve, thus cutting off main reservoir pressure from the engineer's brake valve and the feed valve, preventing the engineer from opposing or preventing the automatic brake application. A cavity 15 in the slide valve 2, with this valve in its operated position, connects a pipe 16 leading to the usual brake pipe 110.

with a pipe 17. The pipe 17 is connected to atmosphere normally through a cavity 18 in the casing of the cut-out valve CO, a port 19 through said valve, pipe 33, and an adjustable 5 restricted orifice 34. The restricted orifice 21 is intended to produce the restricted rate of brake pipe venting required for a service application, as distinguished from an emergency application.

10 It should be understood that the simple construction of brake applying valve AV shown is merely typical of some suitable brake applying mechanism constituting the last device in an operative chain of a speed control or 15 train stop system; and since the particular construction of this application valve AV forms no essential part of the present invention, no attempt has been made to illustrate or describe various additional features of construction, such as predetermined reduction devices, equalizing discharge pistons, and the like, which would be employed to advantage in practice.

15 In the simplified form of cut-out valve CO shown, a valve or slide 20, formed with a handle to facilitate its manipulation, is supported in a casing with suitable gaskets and packings, together with ports and cavities, so that various pressure connections are made 20 and broken as this valve or slide is shifted back and forth. The valve 20 is shown in the normal inactive or cut-in position, and may be sealed or locked in this position as indicated by the seal 21, or may be equipped with 25 a key lock, counter, or similar means designed to prevent operation of this valve without detection.

20 In the normal position of valve 20 shown, a free passage for venting of the brake pipe is provided from pipe 17 through cavity 18 and port 19 to the pipe 33. Upon movement of the valve 20 to the right, to its active or cut-out position, main reservoir pressure is supplied from pipe 29 through a port 22 to the 25 pipe 14 leading to the engineer's brake valve, so that, even if the application valve AV is in the brake applying position due to some mechanical or electrical failure of the train control equipment, main reservoir pressure is still supplied to the engineer's brake valve, 30 permitting the brakes to be released and handled manually in the usual way.

35 When the engineer has been obliged to cut out the train control equipment on account of some defect, it is desirable that the engineer should be kept constantly advised of this condition and can not fail to recognize that he must control his train without the aid or supervision of the automatic train control system. While the ringing of a bell or similar 40 audible signal continually, while the equipment is cut out, might serve this purpose, a special indicating means is provided by this invention. This indicating means should 45 be located at some point in the engineer's

cab where he is sure to see it, either in direct line with his vision while looking out of the cab window or in some other place where he will frequently look. In the particular embodiment of the invention 50 illustrated, the indicating means is associated with the usual air pressure gauge of the air-brake system on the assumption that engineers frequently look at this gauge in performing their ordinary duties. In the simplified construction shown, the front plate of the gauge G is partly cut away to leave two sector shaped openings 23; and behind this front plate is pivotally supported an indicating disc 24 (see Fig. 3) having two sectors 55 colored red or otherwise made distinguishable in a marked manner. This indicating disc 24 is connected by a link 25 to the end of a Bourdon tube 26 of the usual type and construction. When the cut-out valve 20 is moved to the right hand cut-out position, the pressure from the main reservoir is supplied from pipe 29 through port 27 and pipe 28 to the Bourdon tube 26, thereby expanding this 60 tube in the usual way and rocking the disc 24 to bring the colored portions opposite the openings 23, thereby giving an arrestive and distinctive indication. When the cut-out valve 20 is in the cut-in position shown, the Bourdon tube 26 is exhausted through a cavity and port 32, and contracts to expose the plain portions of the disc 24. Obviously, other types and constructions of indicating means could be employed for the same purpose.

65 According to the present invention, the engineer is required to take appropriate action at frequently recurring intervals of time in order to prevent an automatic brake application while the cut-out device CO is in its cut-out or operative position. This not only 70 serves to prevent the engineer forgetting that the train control apparatus is cut out, but also automatically stops the train if the engineer should die or become incapacitated, thereby preventing the train from running 75 very long without being either under the control of some automatic train control system or a live engineer. Accordingly, the movement of the cut-out valve 20 to the right-hand active position, by itself, is not sufficient to prevent a brake application with the application valve AV in the brake applying position, because the venting of the 80 brake pipe pressure through the pipe 17 is not shut off permanently, but can take place through a pipe 30 and a large exhaust port 31, unless the engineer repeatedly manipulates the time controlled device or timing mechanism T to keep this exhaust port 31 closed. The port 31 is intended to exhaust 85 the brake pipe at such a high rate that the engineer cannot recharge fast enough to prevent an application.

90 The time controlled device T comprises a supporting frame or casing 35, in one end

of which is journaled a hollow shaft or spindle 36. The bore in this spindle 36 is square, or some other expedient employed, to afford a slideable but non-rotatable connection to the long hub 37 of a gear 38. The spindle 36 is held against endwise movement in its bearing in the casing 35 by a flange 39 and a collar 40 held in place by a set screw. In the hub 37 of the gear 38 is screw-threaded a shaft 41, which is suitably journaled at its other end in the casing 35 and is provided at that end with a crank or handle 42. To the projecting end of the shaft 41 is pinned a cylindrical spring housing 43 and within this housing is a heavy spiral or coil flat spring 44, similar to a clock spring, which is secured at its outer end to the casing 43 by a bolt or rivet 45 and at its inner end to the hollow spindle 36 by a similar fastening member 46.

In the top of the casing 35 is a bearing pin 50 on which is rotatably mounted an escapement wheel 51, which has integral therewith a long pinion 52 meshing with the gear 38. Pivotally supported on a fixed stud 53 is a pallet 54 engaging the teeth of the escapement wheel 51, this pallet carrying a pendulum-like weight 55 and acting to retard rotation of the escapement wheel 51, pin 52, and gear 38 in either direction.

Also fixed to the shaft 41 is a ratchet wheel 56; and supported on the casing 35 is a pawl 57, pressed by a spring 58 into engagement with said ratchet wheel (see Fig. 4). This pawl and ratchet permit clockwise rotation of the shaft 41 but prevent counter-clockwise rotation. Integral with the hub of the ratchet wheel 56, or otherwise fixed to the shaft 41, is a stop 59 arranged to engage a projecting lug or stop 60 on the face of the gear 38.

Below the gear 38 is pivotally supported a T-shaped lever, having an upright arm 61 and sidewise extending arms 62 and 63. The upright arm 61 carries a roller 64 arranged to be engaged by the face of the gear 38. One extending arm 62 is pulled downward by a spring 65, suitably anchored at one end, against the fixed stop 66. This extending arm 62 when raised, as shown, engages the stem of a valve 67, adapted to be pressed down by a spring 68 and close the exhaust port 31. The other extending arm 63 is arranged to engage the cam shaped end of an arm 69 operating a valve which, when opened, supplies air pressure or steam to a suitable whistle W.

The parts of the time controlled device T are shown in the inactive or run-down position, the valve 67 being open. When the handle 42 is turned in a clockwise direction, the spring housing 43 is likewise rotated; and since the inner end of the spring 44 is held against rapid movement by the escapement mechanism which prevents the escapement wheel 51, pinion 52, gear 38 and hollow spindle 36 turning faster than a certain rate, the

spring 44 is wound up. Also, as the shaft 41 is turned, the gear 38 is moved to the right, being advanced on the threads of the shaft 41 in much the same way as the nut on a bolt is advanced when the nut is held from turning and the bolt turned. After the gear 38 has moved endwise to the right for a short distance, the spring 65 pulls down the extending arm 62 and allows the valve 67 to be closed by the spring 68, and the other extending arm 63 is moved upward to the position indicated by dotted lines. The whistle W is sounded momentarily during this movement, but this is not essential. After the gear 38 has moved to its righthand extreme position, the stop 60 thereon engages the stop 59 on the shaft 41, preventing further relative rotation of said shaft and gear and preventing further rotation of the handle. The pawl 57 and ratchet wheel 56 prevent the return rotation of the shaft 41 in the counter-clockwise direction. The engineer turns the handle 42 as far as it will go and the device T is then in its wound up condition. After the winding operation is completed and in fact during that operation to a small degree, the escapement wheel 51 is being gradually turned at the slow rate permitted by the pallet 54, the spring 44 providing the driving force. The gear 38 turns with the escapement wheel 51, and with the shaft 41 stationary at the end of the winding operation, said gear 38 moves endwise to the left; and after the lapse of a predetermined interval of time for which the device is designed, this gear 38 engages the roller 64 and rocks the T-shaped lever. Before the arm 62 is moved upward far enough to open the valve 67, and thereby permit a brake application, the arm 63 engages the arm 69 and sounds the whistle W, thereby advising the engineer that the time interval has nearly expired and that it is necessary for him to wind up the device T again to prevent the brakes being applied. If the engineer is dead or incapacitated, or for any other reason fails to wind up the device T soon enough, the valve 67 is opened and the brakes are applied.

From the foregoing explanation of the construction and operation of the time control device T, it will be evident that the engineer may rewind this device as frequently as he wishes but is obliged to rewind it at least as often as the time interval for which the device is set. This time interval may be several minutes or less than a minute, as desired. It will also be observed that the engineer cannot defeat the purposes of the device by fastening the handle 42, since the device operates upon continued movement of the handle 42 in the same direction rather than by a forward and backward movement. It is, of course, to be understood that the vital operating parts, except the handle 42, are intended to be enclosed in practice in a suitable

locked or sealed casing beyond the access of the engineer.

In order to simplify the illustration and explanation of the invention, no particular means for controlling the valve EPV has been shown, but it should be understood that this valve EPV is intended to be included in a normally closed circuit which is interrupted automatically by a suitable car-carried apparatus at the time it is desired to produce an automatic brake application. The particular type of car apparatus for controlling the valve EPV is not material to the present invention and may take various forms, being an automatic stop, speed control system, or any other form of an automatic train control system, broadly considered. Also, it should be understood that, by simple adaptations or modifications, which will be apparent to those skilled in the art, other forms of brake control apparatus may be used in connection with the cut-out device embodying this invention, instead of the application valve APV shown.

Having shown and described a rather simple brake applying mechanism, together with a rather specific form of cut-out device, it is desired to be understood that this has been done to facilitate the description of the invention, rather than for the purpose of disclosing the exact structure preferably employed in practice, and that various changes, modifications and additions may be made to adapt the invention to the particular train control or brake applying mechanisms in connection with which it is to be used, without departing from the scope of the invention, or idea of means underlying the same.

What is claimed as new and is desired to be secured by Letters Patent is:—

1. In an automatic train control system, the combination with an air-brake system, of automatically controlled mechanism controlled from the trackway for producing a brake application, and a cut-out device for preventing such brake application independently of the condition of said mechanism, said cut-out device being effective only if manually operated repeatedly at less than a definite predetermined interval of time.

2. In a train control system, the combination with the usual system of air-brakes having a brake pipe, an automatically electrically controlled brake controlling valve acting to cause venting of the brake pipe and thereby produce a brake application, and manually operable means for preventing such venting of the brake pipe independently of the position of said brake controlling valve, said means after once manually operated being effective for a definite limited period of time only and capable of periodic manual operation to make it continuously effective for an indefinite period of time.

3. In an automatic train control system including a brake setting appliance controlled from the trackway and acting upon the usual air-brake system to produce an automatic brake application, a manually operable cut-out device for preventing such brake application irrespective of the operated condition of said appliance and comprising time controlled means which must be operated at least once in a predetermined interval of time in order to maintain said cut-out device effective.

4. In an automatic train control system, the combination with the usual air-brake system including a main reservoir, engineer's brake valve, and brake pipe, an automatically controlled brake application valve acting when operated to cut off main reservoir pressure from the engineer's brake valve and vent the brake pipe, a cut-out device manually operable to supply main reservoir pressure to the engineer's brake valve and prevent the venting of the brake pipe independently of the operated position of said application valve, said cut-out device preventing the venting of the brake pipe only if manually operated repeatedly at least as often as a predetermined interval of time.

5. A cut-out device for automatic train control systems comprising, time controlled mechanism adapted to assume an ultimate condition after the lapse of a predetermined time, and a manually operable handle movable only in one direction for restoring said mechanism away from its ultimate condition, said handle being ineffective to prevent change of said mechanism toward its ultimate condition.

6. A manually operable time controlled device for train control systems comprising, a member movable to an ultimate position, a spring for driving said member, means for limiting the return of movement of said member toward its ultimate position, and a handle for restoring said member away from its ultimate position and at the same time tensioning said spring, said handle being ineffective to prevent movement of said member toward its ultimate position.

7. A manually operable device for train control systems having a limited time of effective action and requiring repeated manipulation, comprising a member movable from an initial position to an ultimate position, means limiting the return of such movement, and a manually operated device for restoring said member to its initial position but incapable of holding said member in said initial position.

8. A manually operable brake controlling device for train control systems comprising, means constantly changing to an ultimate condition, and a handle operable in one direction only for restoring said means away

from its ultimate condition without preventing said means from thereafter changing toward said ultimate condition.

9. A manually operable device for train control systems having a limited time of effective operation, comprising means automatically and continually changing to an ultimate condition, a manually operable device for restoring said means away from its ultimate condition without preventing its return, and signaling means automatically operated a short time before said means assumes its ultimate condition.

10. In an automatic train control system, the combination with an automatically controlled brake setting appliance, of a manually operable cut-out device for preventing a brake application independently of the condition of said appliance, said device including time controlled mechanism and an operating handle and being effective only if said handle is repeatedly moved in the same direction within less than a predetermined interval of time.

11. In an automatic train control system, the combination with an automatic brake setting appliance, of a manually operable cut-out device for preventing a brake application independently of the condition of said appliance, and means for giving an indication while said cut-out device is in its active cut-out condition.

12. In a train control system, the combination with brake control apparatus on a vehicle, of a cut-out valve for rendering said apparatus ineffective to control the vehicle irrespective of its operated condition, and indicating means on the vehicle located at a point where the operator of the vehicle has occasion to look when attending to his duties, said indicating means being automatically operated when said cut-out valve is placed in its active cut-out position.

13. A time controlled manually operable device for train control systems comprising, a member movable to an extreme active position, a spring and escapement mechanism for moving said member to said extreme position at a restricted rate, and manually operable means for tensioning said spring and moving said member away from said extreme position, said means being incapable of holding said member.

14. In an automatic train control system, in combination with an air brake system, automatic electrically controlled mechanism tending to assume an active condition and to cause an automatic application of the brakes when in such condition, and a device acting if actuated to prevent such brake application while said mechanism is in its active condition, said device being maintained actuated only if a manually operable member is operated at predetermined definite time intervals.

15. In an automatic train control system,

in combination with an air brake system, automatic electrically controlled mechanism tending to assume an active condition and to cause an automatic application of the brakes when in such condition, a device effective if in its active condition to permit a manual release of the brakes while said mechanism is in a condition to cause an automatic application of the brakes, said device being maintained in its active condition only if a manually operable member is operated repeatedly at less than a predetermined fixed time interval.

16. In an automatic train control system, in combination with an air brake system, automatic brake applying means tending to assume an active condition and acting to cause an automatic brake application when in such condition, time controlled mechanism adapted to operate from an initial condition to an ultimate condition after a lapse of a predetermined time, and a manually operable handle movable only in one direction for restoring said mechanism from said ultimate condition to said initial condition but ineffective to prevent the operation of said mechanism toward said ultimate condition, said mechanism acting when in said initial condition to prevent said automatic brake application when said brake applying means is in its active condition.

17. In an automatic train control system, in combination with an air brake system, automatic brake applying means tending to assume an active condition and acting to cause an automatic brake application when in such condition, time controlled mechanism for preventing said automatic brake application comprising a member movable to an extreme active position, a spring and escapement for moving said member to said extreme position at a restricted rate, and manually operable means for tensioning said spring and moving said member away from said extreme position, said manually operable means being incapable of holding said member, and said member acting when moved away from said extreme position to prevent an automatic brake application independently of the condition of said brake applying means.

18. In an automatic train control system, in combination with an air brake system, an automatically electrically controlled mechanism for producing a brake application, and a cut-out device for preventing such brake application for an indefinite period of time independently of the condition of said mechanism, said cut-out device being effective only if manually operated repeatedly spaced less than definite predetermined interval of time.

19. In an automatic train control system, the combination with an air-brake system, of automatic brake applying mechanism tending to assume an active condition and cause an automatic application of the brakes, a valve

acting if closed when said brake applying mechanism has assumed its active condition to prevent such automatic brake application, and means tending to open said valve ineffective only if manually operated repeatedly at least once per unit of time.

20. In an automatic train control system including a brake setting appliance acting upon the usual air-brake system to produce a brake application by venting the brake pipe through an exhaust port, a manually operable cut-out device having a tendency to open said exhaust port rendered ineffective only if operated repeatedly at least once per unit of time.
- 10 21. In an automatic train control system, in combination with an air brake system, an automatically controlled application valve, acting to impose an automatic brake application when in its application position, a valve 20 tending to assume the closed position acting

if closed to prevent an automatic brake application when said application valve is in the application position, and manually operable means tending to open said valve and acting if operated repeatedly at less than predetermined definite time intervals to permit closure of said valve.

22. In an automatic train control system, in combination with an air brake system, automatic brake applying mechanism tending to assume an active condition under given trackway conditions and continue in such condition until trackway conditions change, to cause an automatic brake application; a valve acting when closed to prevent an automatic brake application, and manual means tending to open said valve requiring periodic operation to prevent such opening.

In testimony whereof I affix my signature.

RICHARD C. LEAKE.
